Patented Dec. 9, 1924.

UNITED STATES PATENT OFFICE.

EDGAR C. BEECROFT, OF PELHAM MANOR, NEW YORK.

CRUTCH OR LIKE ARTICLE.

Application filed June 27, 1919. Serial No. 307,113.

To all whom it may concern:

Be it known that I, EDGAR C. BEECROFT, a citizen of the United States of America, residing in Pelham Manor, N. Y., have invented new and useful Improvements in Crutches and like Articles, of which the following is a specification.

My invention relates to crutches and like articles, and more particularly to a device for preventing such articles from slipping upon ice or other slippery surface. The general object of my invention is to provide an improved device of this character.

None especially any invention relates to a device such as is shown and described in my United States Patent, No. 1,284,991, dated November 19, 1918, and having means for engaging and securing a firm grip on the slippery surface, the said means being movable with respect to the crutch to permit positioning thereof either in operative position or in inoperative or retracted position in which the ordinary use of the crutch is permitted. My invention, herein disclosed and claimed, is an improvement upon that described in the said patent.

Various objects, features and advantages of the invention will more fully appear from the following detailed description, taken in connection with the accompanying drawing, forming a part of the specification and illustrating the preferred embodiment of the invention.

In the drawing:

Fig. 1 is a side elevation of the lower or tip portion of a crutch provided with said embodiment of the invention.

Fig. 2 is a view of the same partly in side elevation and partly in section taken on line 2-2 of Fig. 1.

Fig. 3 is a top plan view of the same.

Fig. 4 is a section taken on line 4-4 of Fig. 2.

Fig. 5 is a section taken on line 5-5 of Fig. 2; and Fig. 6 is a bottom plan view of the same embodiment of said invention.

Referring to the drawing, the anti-slipping device is provided with a body portion 1, which, as shown, is in the form of a casting secured to the lower or tip portion 2 of the crutch, desirably slightly above the usual rubber ferrule 3 at the tip of the crutch. The body member, as shown, has a substantially cylindrical outer wall portion 4, from which extend substantially parallel walls 5 and 6, bearing upon the crutch. The

walls 5 and 6 have edge portions 7 and 8 respectively shaped to conform to the crutch; and the body member 1 is secured to the crutch, as by screws 9 passing into the crutch through dogs 10 projecting from the walls 5 and 6 respectively.

The means for securing a grip on the slippery surface comprises a tread 10 carried at the lower end of a rod 11, the rod 11 being carried by the body member 1. The tread, as shown, is provided with an extended flat lower surface which has sharp points 12 projecting therefrom for preventing slipping of the tread upon the ice or other slippery surface when the tread is engaged therewith. The tread is mounted upon the rod 11 so as to be capable of limited universal movement with respect thereto; whereby the lower surface of the tread is adapted to rest flat upon the ground even though the crutch, as is usual in its use, is inclined at an angle to the vertical. The rod 11, as shown, is of cylindrical or tubular form. Referring to Fig. 2, the tread 10 is provided with a projection 14 extending into the lower end of said rod and of smaller diameter than the inner bore of rod 11, the projection having at one end a head of spherical shape fitting loosely within the rod 11, as shown at 15. The tread is held against displacement from the rod 11 by means such as the screw 16, which passes through an opening 17 in the tread and is threaded into the rod 11. The opening 17 is of larger diameter than the body or shank of the screw 16 so that a limited amount of universal movement between the tread and the rod 11 is permitted by the screw.

The rod 11 projects downwardly below the screw 16 so as to be adapted to be engaged by the portion 14 of the tread to limit the motion of the tread away from its normal position shown in the drawing.

A stop 18 is secured within the rod 11, as by a screw 19, this stop being positioned with its lower surface a distance from the screw 16 equal to the radius of the spherical portion 15 of the tread so that the said portion will engage the lower surface of the stop in all positions of inclination of the tread 10 permitted by the tubular rod 11. The tread, as shown, is approximately semi-circular in plan, the axis of the rod 11 passing through the centre of the circle of which the edge portion of the tread is the circumference.

When the tread is in operative position, it

projects inwardly under the tip of the crutch, as shown in Figs. 2 and 6, and is arranged in a convenient position to take the downward pressure of the crutch upon the same. When it is in inoperative position, it is arranged on the side of the crutch within the apron like casing 20 at the bottom of the body member 1, the said casing extending around and very close to the outer edge of

the tread. To permit positioning of the tread either in operative or inoperative position, the rod 11 is supported, both for longitudinal movement and also rotation, by inwardly directed walls 21 and 22, which are desirably integral with the member 1. A projection or finger piece 24 extends through a slot in the member 1 and is secured to rod 11. The slot referred to has a portion 25 extending longitudinally of the rod 11 and of the body member 1, a portion 26 extending from the portion 25 substantially horizontally or at right angles to the portion 25, and recesses 27 and 28 respectively in the top and bottom of the portion 26 and at the end thereof remote from the portion 25. The length of the portion 26 of the slot is such as to permit the projection 24 and the rod 11 to rotate through an angle of ninety degrees about the axis of said rod. When the tread is in lowered or operative position, as shown in Figs. 1 and 2, the projection 24 is in the recess 27, being held against lateral and upward movement relatively to the body member 1 and the crutch by the walls of said recess. Although the upward thrust of the tread might be applied to the member 1 through the projection 24, I prefer to use a supplementary member 30 for this purpose, the member 24 serving only for the purpose of shifting the position of the tread and assisting in retaining the same in position. The member 30, as shown, is in the form of a pin projecting through the rod 11 and adapted to pass through a slot 31 in the wall 21 when the projection 24 passes through the lower end of the vertical portion 25 of the slot in the member 1. When the projection 24 is moved laterally in the portion 26 of the said slot, the pin 30 is moved out of register with the slot 31 and when the projection 24 has passed into the recess 27, the projecting ends of the pin 30 engage the lower surface of the wall 21.

A spring 32 is connected at its upper end to a cap 33 and at its lower end to the member 24, which, as shown, is in the form of a screw passing through rod 11 and seated in opposite walls thereof. This spring not only exerts an upward pull upon the rod 11 with respect to the body member 1 and the crutch, but it also tends to turn the tread and the supporting rod 11 about the axis of the latter so as to move

the projection 24 laterally away from the vertical part 25 of the slot in the body member and towards the recess 27. The spring thus counteracts any tendency of the said projection to move towards the vertical part 25 of the slot and thereby resists accidental release of the tread from operative position. The tension of the said spring draws the projection 24 firmly upwardly into the retaining recess 27. To permit variation or adjustment of the torsional force in the spring 32, the cap 33 is movably mounted in the body member 1, being, as shown, provided with a portion 34 square in horizontal section which fits within the upper wall of the body member. The upper end of the cap projects beyond the portion 34 and rests upon the top of the member 1. To vary the torsion of the spring, the cap is lifted to remove the portion 34 thereof from the top wall of the body member 1, the cap being then turned about the axis of the spring to impart the desired tension thereto, whereupon by replacing the cap in operative position upon the top of the member 1, the cap will be held against rotation and the desired torsion retained in the spring. With the construction shown, the torsion of the spring can be conveniently varied by quarter turns. By making the plug portion 34 of the cap of suitable shape, the spring may be held in position after an adjustment of any desired fraction of a turn.

To move the tread from operative position to inoperative position, the projection 24 is depressed so that it will pass into the portion 26 of the slot in the body member 1, and then shifted laterally in the slot until it reaches the portion 25 of the slot, whereupon the spring 32 will retract the rod 11 together with the tread 10 with respect to the crutch. The tread after the lateral movement of the projection 24, is arranged with its straight side adjacent to and slightly to one side of the crutch, and when retracted it is arranged within the apron like casing 20. The said casing prevents objectionable outward movement of the tread and also prevents points or teeth 12 thereof from catching in clothing when the tread is in inoperative position. The upward movement of the tread, as shown, is limited by engagement of the projection 24 with the upper end wall of the slot 25. To move the tread downwardly into operative position it is simply necessary, as will be evident, to press the projection 24 downwardly, then to move the same laterally into the portion 26 of the slot and to release the same, whereupon the spring 32 will move the said projection into the recess 27, the tread being then retained in operative position. In case the tread should get stuck to the

ground, the projection 24 will be drawn downwardly into the recess 28 upon the lifting of the crutch. As, however, the walls of this recess hold the projection from 5 movement toward the portion 25 of the slot in body member 1, the danger of accidental release of the tread from operative position is practically obviated. As soon as the downward pull on the tread is released the 10 spring 32 will draw the projection 24 back into the recess 27. In order that the anti-slipping device may be made as compact and of as small weight as possible, I desirably incline the body 15 member 1, and the rod 11 inwardly towards the crutch at the upper end as clearly shown in Fig. 2. This arrangement enables the tread 10 to pass readily past the ferrule 3 while permitting the upper end of the device 20 to be arranged close to the crutch. While I have shown the preferred form of the invention, it is to be understood that I am not limited to this precise form, and that many changes and modifications may be 25 made in the structure shown without departing from the spirit of my invention.

What I claim as new and desire to secure by Letters Patent is:

1. An article such as a crutch having a 30 member provided with means adapted to secure a firm hold on a slippery surface, said member being movable relatively to the article into operative or inoperative position, means for retaining said member in position 35 relatively to the article including a projection on said member, a second member having a slot in which said projection is movable, said slot having a portion extending longitudinally of the article, another portion 40 extending from said longitudinal portion transversely of the article, and a spring tending to rotate said first-named member so as to move said projection laterally in the last named portion of said slot away from 45 the first named portion thereof.

2. An article such as a crutch having a 50 member provided with means adapted to secure a firm hold on a slippery surface, said member being movable relatively to the article into operative or inoperative position, means for retaining said member in operative position relatively to the article including a spring tending to move said member upwardly longitudinally of the article, a 55 projection on said member, and a second member having a slot in which said projection is movable, said slot having a portion extending longitudinally of the article, and another portion extending from said longitudinal portion transversely of the article, 60 and provided respectively above and below the same with retaining recesses, the walls of which prevent rotation of the member.

3. An article such as a crutch having a 65 member provided with means adapted to se-

cure a firm hold on a slippery surface, said member being movable relatively to the article into operative or inoperative position, means for retaining said member in position relatively to the article including a spring tending to rotate the member about its axis, and means for varying the torsion of said spring. 70

4. An article such as a crutch provided with an anti-slipping device comprising an elongated member inclined upwardly and inwardly towards the article and a tread carried by said member and having an extended lower surface adapted to secure a hold on a slippery surface, said member being movable to carry said tread into operative or inoperative position, said tread being mounted for movement relatively to the article to permit the inclination of the lower surface of the tread with respect to the article, whereby the tread is adapted to make substantially flat contact with the slippery surface when the article is at an angle to the vertical, the inclination of said elongated member permitting the tread to 80 pass readily past the tip of the article. 85

5. An article such as a crutch having a member provided with a tread adapted to secure a firm hold on a slippery surface, said member being movable relatively to the article into operative or inoperative position, means for retaining said member in operative position relatively to the article including a spring tending to move said member upward longitudinally of the article, a 90 projection on said member, and a second member having a slot in which said projection is movable, and through which it protrudes and in which it is adapted to be held. 95

6. An article such as a crutch having a member provided with a tread adapted to secure a firm hold on a slippery surface, said member being movable relatively to the article into operative or inoperative position, means for retaining said member in operative position relatively to the article, including a spring tending to move said member upward longitudinally of the article, a projection on said member, and a second member having a slot in which said projection is movable, said slot having a portion extending longitudinally of the article, and another portion extending from said longitudinal portion transversely of the article. 105 110

7. An article such as a crutch having a member provided with a tread adapted to secure a firm hold on a slippery surface, said member being movable relatively to the article into operative or inoperative position, means for retaining said member in operative position relatively to the article, including a spring tending to move said member upward longitudinally of the article, a projection on said member, and a second member having a slot in which said projec- 115 120 125 130
